(57) **CLAIM**

We claim the ornamental design for a golf putter head, as shown and described.

DESCRIPTION

FIG. 1 is a top, side perspective view of a golf putter head; FIG. 2 is a top view of the golf putter head of FIG. 1; FIG. 3 is a rear view of the golf putter head of FIG. 1; FIG. 4 is a front view of the golf putter head of FIG. 1; and, FIG. 5 is a side view of the golf putter head of FIG. 1. The ornamental design that is claimed is shown in solid lines in the drawings. The broken (dashed) lines shown in FIGS. 1 through 5 are included for the purpose of illustrating environmental elements only and form no part of the claimed design.
